OPERATING MECHANISM FOR LIFTING JACKS

George E. Tintera, Berwyn, and William E. Gahl,
Brookfield, Ill., assignors to Templeton, Kenly
& Company, Limited, Chicago, Ill., a corpora-
tion of Illinois

Application March 1, 1937, Serial No. 128,342

2 Claims. (Cl. 74—157)

This invention relates to improvements in operating mechanism for lifting jacks and it consists of the matters hereinafter described and more particularly pointed out in the appended 5 claims.

The lifting jacks with which the present invention is more particularly concerned, are of the kind embodying therein a shaft and a lever operated pawl and ratchet mechanism whereby 10 the shaft may be turned in one direction or the other to raise or lower the load.

One of the objects of the present invention is to provide an improved mechanism of this kind, which is simple in construction, is positive in 15 operation and is not only easy to shift from load-raising condition to load-lowering condition, but visibly presents to the operator, the condition for which the mechanism is set.

A further object of the invention is to provide 20 a mechanism of this kind which may be assembled in a substantially grit-proof casing, so as to protect the interior mechanism from the abrading action of grit and the like and thus increase the period of usefulness of the mechanism without servicing or repair.

A further object of the invention is to provide 25 an improved mechanism whereby the pawl may be rocked from one operative position to another with respect to the associated plunger from one side to the other of a line passing through the axes of said pawl and ratchet wheel respectively.

The above mentioned objects of the invention, as well as others, together with the several advantages thereof, will more fully appear as the 30 specification proceeds.

In the drawing:

Fig. 1 is a side elevation of a jack operating mechanism, embodying the preferred form of the 40 invention with parts of the associated casing shown in section better to illustrate the interior parts thereof.

Fig. 2 is a sectional view through the structure shown in Fig. 1, as taken on the line 2—2 of Fig. 1.

Fig. 3 is another sectional view through a part of the improved jack mechanism, as taken on the line 3—3 of Fig. 1.

Fig. 4 is a perspective view of a certain actuating member embodied in the improved mechanism and which will be more fully referred to later.

Fig. 5 is a view in side elevation, on a reduced scale, showing that side of the improved mechanism, opposite the side appearing in Fig. 1.

Referring now in detail to that embodiment of the invention illustrated in the accompanying drawing, 5 is a driving shaft of a conventional so-called journal jack and 6 is a ratchet wheel non-rotatively secured on a portion 7 of 5 said shaft, spaced from an extremity 8 thereof. As herein shown, said shaft portion 7 is of a rectangular cross section and the ratchet wheel 6 has a corresponding opening that snugly fits thereon.

9 indicates a hollow casing or housing that encloses the ratchet wheel and is turnable about the axis of the shaft in opposite directions. As shown herein, said housing includes spaced side walls 10 and 11 respectively, front and rear walls 12 and 13 respectively, an end wall 14 rounded to be concentric with the axis of the shaft 5, and a second end wall 15. A socket 31 is made integral with one of the walls 10—11 to receive a lever, whereby the casing is rocked back and forth 10 about the axis of the shaft 5, in the manipulation of the jack for raising or lowering a load.

The ratchet wheel 6 is herein shown as having V shaped teeth on its periphery. 16 indicates a pawl journalled on a shaft or pin 17 25 spaced from and parallel with the shaft 5. The shaft 17 is suitably secured at its ends in openings provided therefor in the walls 12 and 13 respectively and it is about the axis of said shaft 30 that the pawl is rockable from one operative position to another, as will soon appear.

The pawl 16 is a two-ended one and therefore includes ends or arms 18 and 19 respectively arranged on the same side of the axis of the shaft 17. Each pawl end is provided with V shaped 35 teeth 18^a and 19^a respectively for engagement with and disengagement from the similar teeth of the ratchet wheel. The pawl is of a substantially truncated triangular shape and its truncated or flat end 20, on the other side of the axis 40 of the shaft or pin 17 is arranged substantially parallel with a line extending between like points of the ends or arms 18 and 19.

21 indicates an actuating member in the form of a relatively short cylindrical member or pin 45 slidable through the top end portions of the casing walls 10 and 11 in a plane at a right angle to the line passing through the axes of the shafts 5 and 17 respectively. Said actuating member is 50 of a length greater than the distance between the associated end portions of the walls 10 and 11 respectively at this point. The actuating member 21, which is shown in perspective in Fig. 4, is provided at one side of its mid portion with a longi- 55

tudinal groove 22 and is further provided at its mid portion with a transverse recess 23.

A set screw 24 is operatively engaged in an opening provided therefor in the wall 12 of the 5 casing and this screw has a reduced end portion 25 which engages in the groove 22 of the member 21. The screw 24 therefore, not only limits the endwise shifting movement of said member, but it also prevents said member from turning 10 about its axis.

A yielding element in the form of a plunger 26 is disposed in the recess 23 and a spring 27 is interposed between said plunger and the bottom of said recess. Said spring normally urges the 15 plunger outwardly so as yieldingly to hold its end in operative engagement with a part of the pawl end 20. On one of the walls 12-13 of the casing toward the walls 10 and 11 thereof, are legends reading "Up" and "Down" respectively, as appears 20 in Fig. 5. These legends visually indicate to the operator, by the position of the actuating member 21, the setting of the pawl 16 for a raising or a lowering of the load being operated upon.

When the actuating member or pin 21 is 25 pushed endwise from one limit of its movement to the other, as provided by the engagement of the screw end 25 in the groove 22, the spring pressed plunger 26 moves therewith in engagement with the pawl end 20. As the plunger approaches a line passing through the axes of the 30 shafts 5 and 17 respectively, it yields or recedes into its recess and compresses its spring 27. So soon as the plunger passes said line, it is urged outwardly by its spring and rocks the pawl from 35 one operative position to the other, as appears in full and dotted lines respectively in Fig. 1.

When the plunger is disposed at one side of said line, as shown in Fig. 1, the teeth of the pawl end 19 are engaged with certain of the teeth 40 of the ratchet wheel, at one side of said line passing through the axes of said shafts 5 and 17. Thus, when the casing 9 is turned clockwise, as in Fig. 1, the pawl causes the ratchet wheel to turn therewith to turn the shaft 5. When the 45 casing is turned counterclockwise, the pawl is caused to "click" over the teeth of the ratchet wheel, the plunger 26 yielding in its recess to permit such movement.

In the assembly of the parts, the plunger 26 50 and its spring, the pawl 16 and the ratchet wheel 6 are introduced into the casing through an opening 28 in the casing wall 13 of a diameter somewhat greater than that of the ratchet wheel. This opening is then closed by a flanged retainer 55 plate 29. As shown herein, said plate has a pressed fit in said opening and a set screw 30, threaded partly in said plate and partly in the casing, locks said plate in place. The casing may be provided on its socket 31 with a lug 32 60 whereby the casing may be turned about the

shaft 5 in the "clicking" direction, independently of the lever engaged in said socket.

It is apparent that the pawl is rocked from one operative position into the other by shifting the yielding means or plunger 26 from one side to the other of a line passing through the axes of the shafts 5 and 17 respectively, the yielding means or plunger operating against the pawl to let it click over the ratchet wheel on the back stroke.

While in describing the invention we have referred in detail to the form, arrangement and construction of the parts involved, the same is to be considered in the illustrative sense only so that we do not wish to be limited thereto except as 15 may be specifically set forth in the appended claims.

We claim as our invention:

1. In an operating mechanism of the kind described, a casing, a pawl pivotally mounted in the 20 casing for a rocking movement from one operative position to another, a cylindrical actuating sliding member having a guided longitudinal movement through a part of said casing in two directions, said cylindrical member having a close 25 fit within the ends of the casing to exclude dust and the like, said member having a longitudinal groove and a transverse recess therein, means carried by the casing and engaged in said groove and limiting the longitudinal movement of said member as well as preventing a turning movement of the same about its axis, and yielding 30 means arranged in said recess and engaged with a part of said pawl for holding it in one operative position or the other, said yielding means in 35 the movement of the actuating member from one limit of movement to the other, operating upon said pawl part for rocking the pawl from one operative position to the other.

2. In an operating mechanism of the kind described, a casing, a pawl pivotally mounted in the 40 casing for a rocking movement from one operative position to another, an actuating sliding member having a guided longitudinal movement through a part of said casing in two directions, said member having a close fit within the ends of the casing to exclude dust and the like, said member having a longitudinal groove and a transverse 45 recess therein, means carried by the casing and engaged in said groove and limiting the longitudinal movement of said member, and yielding means arranged in said recess and engaged with a part of said pawl for holding it in one operative position or the other, said yielding means in 50 the movement of the actuating member from one limit of movement to the other, operating upon said pawl part for rocking the pawl from one operative position to the other.
